UNITED STATES PATENT OFFICE.

HUGO SCHWARZENBERGER AND WILLY SCHMIDT, OF NUERMBERG, GERMANY.

EXPANSIBLE HINGE FOR TRUNK CASES.

Application filed June 2, 1927, Serial No. 195,952, and in Germany June 2, 1926.

This invention has reference to trunks, cases and similar receptacles constructed with flexible or rigid walls and provided with extensible hinge or lock bands adapted by telescopic action to afford variable accommodation or capacity for the contents; the hinge or lock bands in some instances comprising telescoping bodies arranged so as to be automatically adjustable or extensible against spring tension upon the latter being overcome as the result of closing the trunk, case or the like.

In the case of flexible walled trunks and the like the walls only become taut when the trunks are fully packed, the said walls lying together under the influence of the straps when the trunk is packed only to a moderate extent. Thus the contents are only slightly protected.

The present invention has for its object to provide an improved construction of hinge or lock band for application to trunks and similar receptacles of the kind herein referred to in which one of the telescopic bodies is adapted for frictional retention in a position of adjustment in relation to the other of said bodies by means of laterally yielding or expanding flaps or spreaders, thereby enabling the adjustment of the hinge or lock band to be easily and conveniently effected in any position that may be required to correspond with the contents or extent of packing of the trunk or the like at the time of use.

In order that the invention may be readily understood and carried into effect same will now be more fully described with reference to the accompanying drawing in which a trunk or the like is represented having the improved hinge or lock band applied thereto, and in which:—

Figures 1 to 3 illustrate, in side elevation the trunk with the parts thereof in various positions.

Figures 4 and 5 show a hinge or lock band; Figure 4 being a longitudinal section and Figure 5 an under side view thereof.

Figure 6 is a view similar to Figure 5 of a portion of the inner body removed from the outer body showing the effect of the spring on the outwardly pressed friction members.

Figures 7 and 8 are views in section taken respectively on the lines A—B and C—D in Figure 4.

Referring to Figures 1 to 3, the trunk con-

sists of the case proper 1 and the lid 2, both of which may be constructed of any suitable material such as leather, vulcanized fibre, cardboard, cane, wood, straw, wickerwork etc., and are rigid in character. The said trunk parts are connected with one another by hinge or lock bands comprising telescopic prismatic bodies 3, 4, Figures 4 to 8, of U-shaped cross section. The body 3 is the outer one and is provided with lateral lugs 5, formed by bending the metal at right angles, which serve in fastening the hinge or lock band to the trunk lid 2 by means of screws or such like, a covering plate 6, holed for the passage of the screws, being interposed between the said body and the surface of the trunk lid, the inner body 4 in its retracted or normal position projects somewhat from the outer body 3 and this projecting part carries a rectangular or square ring 7 which is attached to or engages an eyelet 8 articulated or fixed in the back wall of the case part 1 of the trunk.

The said inner body is provided at the end remote from the ring 7, with laterally spreadable members or flaps 4^a 4^b formed by slitting, as indicated at 4^b, the said body a certain distance at the angles of the base 4^c with the sides the said base being bent into an approximately circular form in cross section as indicated at 10 so as to enclose a spring 9 and retain it in operative relation with the members or flaps 4^a. Thus the said members are subjected to a strong spring pressure which tends to flex or bend the same outwards so as to cause them to frictionally engage the adjacent inner sides of the outer body 3. If desired with a view to increasing the friction the surfaces may be ribbed, roughened or otherwise treated.

By these means a strong friction coupling or connection is effected between the bodies 3 and 4, which renders possible the adjustment of the said bodies relatively in every position without risk of displacement occurring as the result of the pressure incidental to the packed contents of the trunk or the like.

The covering plate 6 is formed with a lug portion 11 which acts as a stop to prevent the inner body 4 being wholly withdrawn from the outer body 3, the spring enclosing part 10 pertaining to the body 4 contacting with the said lug 11 when the inner body is withdrawn to its full extent.

The lock bands are similar in construction

to the hinge bands but the inner body 4, instead of carrying a ring with an articulated eyelet, is fitted with a lock catch 12 of any usual or known kind (see Figures 1 to 5 3).

It will be readily understood that in the case of the trunk, Figure 1, being filled only to the edge of the case part 1, or a little beyond, the lengthening of the hinge and lock bands will not be required and the trunk can be manipulated (opened and locked) in the ordinary manner.

If, however, the trunk case part 1 is filled very perceptibly above the upper edge the lid will lie with its lid wall against the packed contents and the turning of the lid to close the trunk is not effected about the hinge but about the supporting point of the lid through the contents of the trunk. Consequently pressure is exerted on the hinge bands and the bodies 3 and 4 thereof assume the requisite relative positions governed by the extent of packed contents, the movement of the said bodies being limited to that actually required by the contents. The hinge bands may however be lengthened before effecting the closing of the trunk a procedure that may be advantageous when the bands are of stout or very strong construction making the resistance considerable and that of the contents being insufficient to overcome the frictional connection of the bodies comprising the bands.

By means of the rings 7, a kind of double hinging is provided which, while avoiding strains or stress on the hinges and the aforesaid point of support, enables the closing to be effected conveniently and easily with the lengthening of the bands. The actual closing of the trunk is effected by withdrawing the inner bodies of the lock bands and pressing the lock-catches into the locks as will be readily understood.

The form and length of the hinge and lock bands may obviously be varied to suit 45 varying conditions without departing from the essential features of the invention.

Having now particularly described and ascertained the nature of our said invention and in what manner the same is to be performed we declare that what we claim is:—

1. An expandible hinge for trunk cases which comprises a pair of telescoping members provided with means for attachment to the receptacle, the inner member being split 55 at one end, and a spring for forcing opposite portions of said split end into frictional engagement with the outer member.

2. An expandible hinge for trunk cases which comprises a pair of telescoping members provided with means for attachment to the receptacle, the inner member being split at one end, and a spring for forcing opposite portions of said split end into frictional engagement with the outer member, said 65 split end also having a portion bent to form a holder for said spring.

3. An expandible hinge for trunk cases which comprises a pair of telescoping U-shaped members in frictional engagement 70 with each other and having their channel openings directed downwardly, the outermost member having securing means extending horizontally from its side walls, and a horizontal plate in contact with said securing means and having an integral tongue projecting upwardly therefrom into the channel of the inner member and cooperating therewith to limit its longitudinal movement.

In testimony whereof we have signed our names to this specification at Nuremberg, Bavaria, this 13th day of May, 1927.

HUGO SCHWARZENBERGER.
WILLY SCHMIDT.
